UNITED STATES PATENT OFFICE.

CHARLES PUTKOWSKI, OF STATEN ISLAND, NEW YORK, ASSIGNOR OF ONE-HALF TO
Wладислав Бронicki, OF MARINE HARBOR, NEW YORK.

CULTIVATOR.

1,417,942.

Specification of Letters Patent. Patented May 30, 1922.

Application filed August 11, 1921. Serial No. 491,383.

To all whom it may concern:

Be it known that I, CHARLES PUTKOWSKI, residing at Staten Island, in the county of Richmond and State of New York, have invented certain new and useful Improvements in Cultivators, of which the following is a specification.

This invention relates to improvements in cultivators and more particularly to devices for use in hoeing potatoes and similar vegetables.

The principal object of the invention resides in the provision of a device which is so designed as to avoid becoming clogged and which will readily permit stones to pass between the tines, so that they will remain clear for the free passage of the earth.

Another object of the invention is to provide a novel type of means for securing the handle to the blade which is so constructed that said handle may be readily removed and replaced and held solidly in the proper position.

With these and other objects in view the invention consists in the novel construction, combination and arrangement of parts, which will be fully set forth in the following specification, claimed and illustrated in the accompanying drawing, in which,

Figure 1, is an end view of this improved cultivating implement,

Figure 2, is a side view of the blade, showing the handle removed,

Figure 3, is a fragmentary sectional view through the handle connecting socket, and

Figure 4, is a sectional view taken on line 4—4 of Figure 3.

Referring to the drawings in detail the numeral 10, designates the handle of the device in one end of which is fixed a tapered pin 11, the larger end of which is disposed outwardly.

The blade is designated in its entirety by the numeral 12 and comprises an eye member 13, the legs of which are extended as at 14 and gently curve outwardly toward their free ends. The extreme ends of the legs 14 are sharpened as at 15 to provide a weed cutter.

Formed on the right portion of the eye member 13, is a socket member 16, which extends at right angles to the plane of the

blade 12 and is provided with an axial internally threaded bore 17, which opens at its inner end into a reduced bore 18, of a diameter to receive and snugly fit the larger end of the tapered pin 11 previously mentioned. 55

In order to firmly hold the handle in place and yet provide for its ready removal, a ring 19 is split as at 20 and is formed on its outer surface with screw threads for co-operation with the threads in the bore 17. This ring is preferably provided in its outer end with diametrically spaced recesses 21 for the reception of a spanner, by means of 65 which the ring may be tightened into place.

In operation it will be seen that the pin 11 is inserted into the bore 18, passing through the bore 17, and forced inwardly until its end abuts the end of the inner bore. When 70 in this position, the split nut or ring 19 is then threaded into the bore 17 and it will be obvious that its inner wall will frictionally engage the tapered pin and upon further tightening on the ring by the use of a 75 spanner, the parts will be firmly held against accidental movement.

While in the foregoing there has been shown and described the preferred embodiment of this invention it is to be understood 80 that certain minor changes in the construction, combination and arrangement of parts may be resorted to without departing from the spirit and scope of the invention as claimed. 85

What is claimed is:—

A garden implement comprising a head, a socket member associated with the head, said socket member having an axial internally threaded opening and a reduced bore 90 at the inner end of the threaded opening, a handle, a tapered pin in one end of the handle arranged in axial alinement therewith, the larger end of said pin being disposed outwardly and adapted to fit the reduced bore in the socket member, and a split ring adapted to fit around the tapered pin and to be screwed into the threaded opening in the socket member, whereby the tapered pin will be firmly held in position in 100 the reduced bore. 95

In witness whereof I affix my signature.

CHARLES PUTKOWSKI.
